Carl Votti,
John Adiedersheim

ATTORNEY.

UNITED STATES PATENT OFFICE.

CARL VOTTI, OF PHILADELPHIA, PENNSYLVANIA.

CALENDAR-CLOCK.

SPECIFICATION forming part of Letters Patent No. 256,255, dated April 11, 1882.

Application filed July 14, 1881. (Model.)

To all whom it may concern:

Be it known that I, CARL VOTTI, a citizen of the United States, residing at Philadelphia, in the county of Philadelphia, State of Pennsylvania, have invented a new and useful Improvement 5 in Calendar-Clocks, which improvement is fully set forth in the following specification and accompanying drawings, in which—

Figure 1 is a front view of the calendar-clock 10 embodying my invention. Fig. 2 is a rear view of a portion thereof. Fig. 3 is a side elevation of a portion thereof. Figs. 4, 5, and 6 are sectional views of detached parts. Fig. 7 is a perspective of the pack or set of calendar-cards.

15 Similar letters of reference indicate corresponding parts in the several figures.

My invention consists of a calendar in the form of a pack or set of disconnected cards—one for each day or interval of time—a box or 20 holder, mechanism operated by a clock or other time-piece or motor, whereby the cards are successively grasped and entirely removed from the holder, each at the interval, and means whereby the withdrawn cards are deposited in 25 a receptacle, from whence they may be gathered and returned to the box or holder.

It also consists in constructing the cards whereby each may be readily grasped without disturbing the adjacent cards and their strength 30 is increased.

It also consists of means for holding the cards in proper position, guiding them true in their motion, and preventing the discharge of more than one card each time.

35 Referring to the drawings, A represents a clock, which, excepting as far as it relates to my invention, may be of ordinary form and construction.

Supported on the frame of the clock is a box 40 or holder, B, open in front, in which is placed upright a number of separated cards, A', formed of paper or other suitable material, having printed or otherwise marked on them the names and numbers of the days and months of the 45 year, or portions thereof, and other information, if desired.

Each card is formed with an opening, a, back 50 of which is a covering-strip, b, secured to the card, the opening being adapted to receive the hook c of a finger, C, and the covering-strip preventing said hooked end engaging with the

contiguous card, as well as serving as a reinforcement for the opening a.

The finger C consists of a transversely-extending rod, which is fitted in eyes or guides 55 d on the holder B, the forward end being bent angularly, first upward, then inward, and finally downward or around, constituting the hook c, as above referred to. The rear end of the piece C has connected to it a toggle, D, 60 which is attached to a crank or wrist pin, e, on a spur or gear wheel, f, whose shaft g is mounted beneath the holder B, and carries at its front end the fan-shaped piece or wing E, whose location is at the front of the lower end of the 65 holder B, and consequently of the cards A'.

Motion is imparted to the spur-wheel f by means of properly-mounted gear-wheels h h' and a spur-wheel, k, on the center post, m, of the clock, the nature of the gearing being such 70 in the present case that the spur-wheel f makes one revolution every twenty-four hours.

Depending from the corner of the holder B, adjacent to the front bend or angle of the finger C, on the inner side thereof, is a bent or 75 angular deflector, F, and bearing against the outer side of said bend or angle is a spring, G, which is secured to the box B.

In order that the cards A' may be held uniformly in position and pressed to the front of 80 the holder, I place within the holder, against the back of the pack of cards, a slide, H, against which bears one or more springs, J, which are secured to the frame or support of the clock or the holder B, as desired. The opposite side 85 of each card is cut away or channeled at coincident places, as at n, and the opposite sides of the inner face of the holder B have angular guide and stop pieces K, the horizontal limbs whereof are above and enter the channels n 90 of the cards, said pieces K being set back from the front flanges, p, of the holder B, the tops of the cards projecting above the box, and being held upright by a guard, L, rising from the box, and furthermore pressed by springs L'. 95

Below the clock case or body containing the movements is an inclined chute, whose forward end projects in front of the dial, so that cards falling from the holder drop on the chute, and are thus directed into the drawer or place of 100 deposit N.

When pendulum-clocks are used the pendu-

lum-arm is open or of the form of a frame, as at P, so as to encircle the chute M, whereby the latter does not interfere with the free vibrations of the pendulum.

- 5 The operation is as follows: When the clock is set in motion the hook *c* of the finger C begins to rise, and by the action of the spring G is moved in against the cards A' as it leaves the advanced end of the deflector F, the rod 10 which constitutes the main portion of the finger sliding freely in the eyes or guides *d*, and the arms of the toggle D being loosely jointed. The wing E is rotated by its shaft *g*, so as to leave the lower edge of the front of the cards, 15 and the hook *c* of the finger lowers and enters the opening *a* of the front or "to-day's" card, engaging with the lower wall of said opening. The further rotation of the finger brings its front bend on the advance end of the deflector 20 F, and so moves the hook of the finger outward from the holder B that the finger draws the front card outward and downward from its place, this occurring at or about the end of the day or other set time. Simultaneously there- 25 with the wing E enters between the bottoms of the first and second cards, and holds the sec- ond card so that it remains immovable. The first card is still further lowered, and when the hook *c* is at or about its lowest point the card 30 drops clear of the hook and falls on the chute M, from whence it is directed to a place of de- posit or collection. The next day's card is thus presented, so that it may be readily seen, the day, month, &c., thus being readily indicated. 35 In due season the finger again rises and draws its hook *c* toward the next front card in the holder, said hook then engaging with the open- ing *a*, removing the card, and the other opera- tions are repeated.
- 40 The horizontal limbs of the angular pieces K serve to guide the cards in their motions to the front, and while the vertical limbs restrain the advance of the cards they also guide the cards as they are being drawn down and out 45 by the finger. The discharged cards may be returned to the holder and located in front of the slide H, and as their order is preserved the proper card will be presented each day or in- terval of time in the automatical manner stated.
- 50 As the cards are collected in the drawer N, they are readily accessible—an important fea- ture for leap-year, when the card of the addi- tional day of February may be applied to the pack, and for other years said card may be re- 55 moved.

If desired, there may be a pack or set of cards for each day, week, and month, or inter-

val, in which case there will be a finger for each set, the operation whereof is similar to that hereinbefore stated.

60

Having thus described my invention, what I claim as new, and desire to secure by Letters Patent, is—

1. A pack of disconnected calendar-cards and a holder therefor, in combination with a time-piece or motor, mechanism operated by said piece for removing the cards, and a chute, whereby when the cards are removed from the holder they drop therefrom and are directed to and deposited by the chute in a separated 65 receptacle, substantially as and for the purpose set forth.

2. A pack of disconnected calendar-cards, a holder therefor, and a time-piece or motor, in combination with a rotary and sliding finger, 75 provided with a downwardly-extending hook, *c*, substantially as described, whereby each card is grasped by the finger, drawn out from holder, and then caused to drop clear of the finger and the holder.

80

3. The card-holder, in combination with the finger C and deflector F, substantially as and for the purpose set forth.

4. The card-holder and the rotary recipro- 85 cating finger, the toggle, and gearing of the motor, combined and operating substantially as and for the purpose set forth.

5. The card-holder, in combination with the rotary wing E, substantially as and for the purpose set forth.

90

6. The cards, with openings *a*, and the cov- 95 ering-pieces *b*, adapted for operation with the finger C, substantially as and for the purpose set forth.

7. The card-holder provided with guides K, 95 and the cards with channels *n*, combined and operating substantially as and for the purpose set forth.

8. The card-holder provided with the guard L and spring L', substantially as and for the 100 purpose set forth.

9. The time-piece or motor, the card-holder, and operating-finger, in combination with the chute M, substantially as and for the purpose set forth.

105

10. In a calendar-clock provided with a de- livery-chute for the purpose set forth, the pendulum having its arm of the form of a frame, as stated.

CARL VOTTI.
